IMPACT TOOL

Edgar R. Whitledge, Mantua, Ohio, assignor, by
mesne assignments, to Reed Roller Bit Com-
pany, Houston, Tex., a corporation of Texas

Application May 2, 1946, Serial No. 666,707

21 Claims. (Cl. 192—30.5)

1

The present invention relates to impact clutches and tools and, more particularly, to portable, rotary, reversible, pressure fluid actuated tools, such as, wrenches, nut runners and the like.

One of the principal objects of the invention is the provision of a novel and improved impact clutch comprising a driving member having a relatively large moment of inertia and a driven member having a relatively small moment of inertia, and highly efficient, simple means for causing the driving member to deliver to the driven member a succession of torsional impulses far greater than the maximum torque of the driving mechanism.

Another of the principal objects of the invention is the provision of a novel and improved impact tool comprising a driving flywheel or momentum member having a relatively large moment of inertia, that is, a relatively large mass offset a maximum distance from the center of rotation, and a driven anvil or member having a relatively small mass and moment of inertia, in combination with highly efficient, simple means for causing the momentum member to deliver a succession of torsional impacts to the driven member.

Another of the objects of the invention is the provision of a novel and improved impact clutch comprising a rotatably supported, driven member or anvil having an external shoulder, a coaxially rotatable driving member or flywheel having a relatively large moment of inertia, and means including an impact member pivotally connected to the driving member for limited angular movement about an axis offset from but parallel with the axis of rotation of the driven member and having a shoulder located adjacent to but adapted to trail the pivotal axis of the impact member with the driving member for causing the driving member to deliver to the driven member or anvil a succession of impacts.

Another object of the invention is the provision of a novel and improved impact clutch and/or tool of the character referred to which is fully reversible.

The invention resides in certain constructions and combinations and arrangements of parts and further objects and advantages thereof will be apparent to those skilled in the art to which the invention relates from the following description of the preferred embodiment described with reference to the accompanying drawings forming a part of the specification in which

2

similar reference characters designate corresponding parts, and in which

Fig. 1 is a side elevational view, with portions in section, approximately on the line 1—1 of Fig. 3, of a hand tool embodying the present invention;

Fig. 2 is a perspective view of a portion of the driving member of the impact clutch shown in Fig. 1;

Fig. 3 is a sectional view, approximately on the line 3—3 of Fig. 1, showing a relative position of the mechanism following impact;

Figs. 4, 5 and 6 are views similar to Fig. 3, but showing the parts in positions which they occupy successively during the cycle of operation;

Fig. 7 is a view similar to Fig. 1, but showing a modified construction;

Fig. 8 is a sectional view, approximately on the line 8—8 of Fig. 7, showing a relative position of the mechanism following impact; and

Figs. 9, 10 and 11 are views similar to Fig. 8, but showing the parts in positions which they occupy successively during the cycle of operations.

Although the invention is susceptible of general application and may be embodied in various construction, it is herein shown and described as embodied in a pressure fluid actuated impact wrench. Except for the parts hereinafter specifically referred to, the tool shown may be of commercial construction and is not shown and described in detail.

Referring to the drawings, the tool shown is designated generally by the reference character A and comprises a reversible motor, including a rotor 10, comprising radial vanes or blades 11 slidably supported within suitable grooves formed in the rotor and through the medium of which the rotor is driven by pressure fluid, preferably compressed air, admitted thereto in a conventional manner by means including a trigger actuated valve, only the trigger 12 of which is shown in the drawings. Since the motor per se forms no part of the present invention, no further explanation is thought necessary other than pointing out that other motors, such as electric, may be employed, as desired.

In addition to the motor already referred to, the tool of the present invention comprises a driven member having a relatively small moment of inertia, a flywheel or driving member having a relatively large moment of inertia, and simple, efficient means for operatively connecting said members whereby the driving member is caused to successively impact the driven member. In

the embodiment shown, the driven member is in the form of a shaft 13 rotatably supported in a bushing 14 fixedly secured in the forward end of a clutch housing 15 detachably connected to the motor housing 16 by screws, not shown. The reversibility of the driving means may be under the control of a sleeve-type reversing valve 17 for directing the pressure fluid to either peripheral extremity of the conventional, lunate, expansible chamber surrounding the rotor 10. The forward end of the shaft 13 is provided with a driving connection adapted to have an adapter, not shown, applied thereto but which, in turn, is adapted to engage a nut, bolt, screw or other similar member which it is desired to tighten or remove. The rear or right-hand end of the shaft 13, as viewed in Fig. 1, is of slightly greater diameter and is provided with two axially spaced, diametrically arranged, arcuately-shaped projections or anvils 18, 19 having radial sides 20, 21 adapted to be impinged by radial surfaces on plate-like impact or hammer members 22, 23 forming a part of the built-up flywheel or driving member or hammer assembly, designated generally by the reference character B. The anvils 18, 19 extend longitudinally of the shaft 13 and are impinged by the impact members 22, 23, respectively.

The impact members 22, 23 have a relatively large mass and are pivotally connected by pins 24, 25 to an integral cage, designated generally by the reference character 26. The pins 24, 25 are located diametrically opposite each other with respect to the axis of rotation of the driven member 13, which member is coaxially supported with respect to the driving or momentum member B and the rotor 10. The cage 26 comprises three spaced disks 27, 28 and 29 connected by relatively narrow webs 30, 31, 32, 33 and the rear or right-hand end thereof, as viewed in Figs. 1 and 2, is keyed to the projecting spindle 34 of the rotor 10. The opposite or front end of the cage 26 is rotatably supported on the shaft 13 by a flanged bushing 35 of suitable wear-resisting material. Alternatively the cage may be of built-up construction.

The cage 26, as shown, is counterbored from the front end so as to permit the insertion of the anvil or rear end of the driven member 13. The impact members 22 and 23 are arranged axially with respect to each other in the cage 26, the impact member 22 being located intermediate the disk portions 27, 28 of the cage and the impact member 23 being located intermediate the disk portions 28, 29 of the cage. The pin 24 is fixedly secured in aligned apertures in the disks 27, 28 of the cage. The disk 29 is provided with apertures 36 counterbored from the front end of the cage to a distance equal to the thickness of the disk 27 to form apertures as continuations of the apertures in the disks 27, 28 within one pair of which the pin 24 is located. The impact member 23 is provided with an aperture 37 diametrically opposite the pin 25 and adapted to align with the apertures in the cage within which the pin 24 is positioned. This aperture, together with the aperture 36, provides an opening whereby the pin 24 may be driven out of the cage when it is desired to disassemble the impact member 22 for purpose of inspection or replacement. The radial flange 38 on the bushing 35 which overlies a portion of the aperture within which the pin 24 is located prevents axial movement of the pin toward the front of the cage in the event the pin becomes loose in the cage and the impact mem-

ber 23 prevents its movement in the opposite direction since the aperture 37 is of less diameter than the diameter of the pin 24.

The impact members 22, 23 are similar in construction and the pin 25 is assembled in the cage 26 in a manner similar to that in which the pin 24 is assembled therein. The shoulder formed by the counterbore in the disk 29 within which the pin 25 is located prevents movement of the pin toward the rear in the event it becomes loose in the cage and the impact member 22 prevents its movement toward the front. An aperture 39 in the disk 22 similar to the aperture 37 in the disk 23 is provided so that the disks are interchangeable, thus facilitating manufacture, assembly and maintenance of the device. The counterbore in the disk 29 in alignment with the pin 24 merely facilitates assembly.

The impact members 22, 23 are narrower than the distance between the webs 30, 31 and 32, 33, respectively, and the spaces between the disk-like portions 27, 28, and 28, 29 within which the impact members are positioned are slightly greater than the thickness of the members 22, 23, with the result that the members 22, 23 are free to pivot between the webs about the pins 24, 25, respectively. The impact members 22, 23 are symmetrical about central planes passing through the centers of their pivotal axes and the apertures 39, 37, respectively, and opposite sides thereof are provided with cut-out portions 40, 41 symmetrically arranged with respect to their pivotal connections with the cage 26. The cut-out portions 40, 41 are of such a character that they produce radial or substantially radial shoulders 42, 43 on each impact member spaced from its pivotal connection with the cage 26. The shoulders 42, 43 face the pivot for the impact member upon which they are formed and are adapted to engage the webs of the cage 26. The shoulders 42, 43 of the impact member 23 are adapted to engage the sides 44, 45 of the webs 32, 33, respectively. The symmetrical construction of the cut-out portions 40, 41 and the shoulders 42, 43 with respect to the pivotal axes of the impact members provides for reverse operation of the device, as will be hereinafter apparent.

The center of each impact member is provided with an aperture 47 defined by arcuately-shaped, alternately arranged surfaces 48, 49, 50, 51 connected by radial or substantially radial surfaces or shoulders 52, 53, 54, 55. The arcuately-shaped surfaces 48, 49 are of equal radii as are the surfaces 50, 51 and all have their centers on a line connecting the centers of the pivot pin 25 and the aperture 37. The surfaces 50, 51 have a common center and the radii thereof are smaller than those of the surfaces 48, 49, the centers of which are spaced apart to provide both the necessary clearance for the anvil 19 and to provide ample size for the shoulders 52, 53, 54 and 55. Although the radii of the surfaces 50, 51 are smaller than the radii of the surfaces 48, 49, they are sufficient to permit the anvil associated therewith to rotate relative to the impact member when the member is swung to one side or the other about its pivotal connection with the cage 26. The construction of the shoulders 42, 43 and the webs of the cage 26 with which they engage is such that the impact members may move a sufficient distance to cause the internal radial surfaces 52, 53, 54, 55 thereof to engage and disengage the external radial surfaces 20, 21 of the anvils 18, 19 with which they cooperate.

The operation of both impact members 22, 23

is alike, therefore, it will be sufficient to describe only the operation of the impact member 23. Assuming that the flywheel or momentum member B is rotating in a clockwise direction, as indicated by the arrow R, the respective parts are shown in Fig. 3 in a position which they may occupy shortly after impact between the shoulder or surface 52 of the impact member 23 with the surface or shoulder 20 of the anvil 19. When the shoulder or surface 52 of the impact member struck or impacted the shoulder 20 of the anvil 19, see Fig. 6, the impact member 23 was rotated by the reaction produced, acting in the direction of the force arrow 60, in a clockwise direction about the pin 25 until the shoulder 42 struck the side 44 of the web 32. This movement of the impact member 23 allowed the shoulder 52 and the surface 50 to pass around the anvil 19. As the shoulders 20, 52 disengage, the flywheel proper accelerates. The center of mass of the impact member is preferably offset with respect to the axis of rotation of the clutch proper and the inertia of the impact member causes it to tend to lag behind the cage 26.

As soon as the surface 50 passes the rear end of the anvil 19 defined by the radial surface 21, which it is about to do, as shown in Fig. 3, the impact member 23 will be free to rotate in a counterclockwise direction about the pin 25. At this time the flywheel proper is accelerating and driving the impact member 23 through the pin 25. The effect of inertia of the impact member 23, as previously mentioned, causes the member to lag behind the flywheel proper whereupon the impact member will move from a position with the shoulder 42 in engagement with the web 32 shown in Fig. 3 to a position with the shoulder 43 in engagement with the web 33. The parts then will be in the approximate position shown in Fig. 5 and the surface 52 again in position to impinge the surface 20 of the anvil 19.

The method of operation just described is automatic but being subject to frictional drag between the parts, it is not positive, and to insure proper setting up of the impact member for the primary impact, the impact member 23 is provided with the internal radial surface or shoulder 54 which cooperates with the surface 20 on the anvil, if necessary, to assure proper resetting of the impact member. As shown in Fig. 3, the arcuately-shaped surface 50 is about to complete its passage over the anvil 19 and the radial surface 54 is approaching the impact surface 20 of the anvil and in the event the impact member 23 has not been reset by inertia, as explained before, and the shoulder 43 not in engagement with the web 33, by the time the shoulder 54 reaches the shoulder 20, the shoulder 54 will impact or strike the shoulder 20, as indicated in Fig. 4. The anvil 19 will offer resistance to rotation of the flywheel proper and will act against the shoulder 54 to rotate the impact member in a counterclockwise direction about the pin 25 until the shoulder 43 strikes the web 33. From the foregoing, it will be understood that the primary purpose of the shoulder 54 engaging the shoulder 20 is to assure proper setting of the impact member shoulder 52 into impact delivering position relative to the anvil shoulder 20.

The force exerted by the anvil 19 against the member 23 will act in the direction indicated by the force arrow 61 and will have a moment arm of magnitude 62 about the center of the pin 25. As the member 23 rotates about the pin 25, the shoulders 20, 54 will be disengaged and the

arcuately-shaped surface 51 will be permitted to pass about the anvil 19, see Fig. 5, whereupon the flywheel continues to rotate freely until impact is made between the surfaces or shoulders 20, 52, see Fig. 6. The condition existing when the shoulder 52 strikes the shoulder 20 is somewhat similar to that existing when the shoulder 54 strikes the shoulder 20 shown in Fig. 4 but the moment arm 63 of the impact force about the center of the pin 25 is much shorter than the moment arm 62, with the result that the impact or blow delivered to the anvil 19 is considerably greater and has considerable force.

It will be noted that the power is transmitted to the impact member through the pivot pin 25 and that the shoulder 52 is adjacent to but trails the axis about which the impact member is pivoted to the driving member or flywheel proper. By varying the radial position of the pivot with respect to the shoulder 52, etc., or by varying the angular position of the shoulder 52 with respect to the pivot, the moment arm 63 can be increased or decreased to vary the blow imparted to the anvil. The same is true of the shoulder 54 which, as shown, leads the pivot for the impact member. When the shoulder 52 strikes the shoulder 20 of the anvil, the reaction produces a clockwise acceleration of the impact member 23 about the pin 25 which because of the relatively large mass of the impact member, adds to the fore of impact, moves the shoulder 42 into engagement with the surface 44 of the web 32, disengages the shoulders 20, 52 and permits the flywheel to resume rotation about the anvil. While the engaging surface 52 and 54 on the impact member 23, and 20 on the anvil 19, respectively, are preferably radial, they may be varied slightly from a true radial position so as to facilitate their disengagement and eliminate all possibility of their hanging together, if desired.

The rotation of the impact member 23 about the pin 25 following impact between the shoulders 20, 52 occurs with considerable acceleration and as the member 23 reaches its limit of movement by the shoulder 42 engaging or striking the web 32, the kinetic energy possessed by the impact member is transferred back to the rotating flywheel and serves to reduce the load of the flywheel upon the driving motor, thus permitting the motor to accelerate and build up speed rapidly between successive impacts. When impact occurs between the shoulders 20, 54 incident to setting up or preparing the impact member for the power or primary impact which takes place when the shoulder 52 strikes the shoulder 20, it occurs only because the frictional forces which may be present resist the automatic counterclockwise movement of the impact member that would otherwise afford uninterrupted passage of the member about the anvil between successive primary impacts. The energy used in this setting-up impact is small, being much less than that imparted by the flywheel or hammer to the anvil upon impact between the shoulders 20, 52 for the moment arm 62 at which the set-up force acts is much greater than the moment arm 63, and the direction of motion of the shoulder 54 is nearly collinear with the force arrow 61, whereas the direction of movement imparted to the shoulder 52 is almost perpendicular to the force arrow 60. Observation of the device in operation indicates that the impact member is frequently set up for the power impact automatically by the inertia thereof, as previously explained,

and without contact between the shoulders 20, 54. The anvils 18, 19 and the pivots for the impact members 22, 23 are offset 180 degrees, and two power blows or impacts which act as a couple are effected upon each rotation of the flywheel assembly B. Obviously any number of impact members and anvils may be employed, in which event any desired number of impacts will be obtained for each rotation of the flywheel.

The anvils 18, 19 and the impact members 22, 23 are symmetrical with respect to a central plane, from which it follows that the clutch or operative connection between the driving member B and the driven member 13 is reversible, therefore, it is only necessary to employ a reversible motor and the tool is suitable for tightening or loosening nuts, bolts, screws and the like. Referring to the operation of the impact member 23, when the drive is reversed the shoulders 21, 53 and 55 correspond with the shoulders 20, 52 and 54, respectively.

With the exception of the driving element of the clutch, the alternative construction shown in Figs. 7 to 11 is similar to that already described and the duplicate parts are indicated by the same reference characters. As distinguished from the construction shown in Figs. 1 to 6 wherein the impact members 22, 23 are pivotally supported in an integral cage 26, the impact members 65, 66 of the alternative construction are disk-like in form and are pivotally connected to diametrically arranged sleeves 67, 68 interposed between spaced plates 70, 71 fixedly secured together so that they operate as a unit by bolts 72, 73 extending through the sleeves 67, 68, respectively.

The plate 71 is keyed to the end 34 of the rotor 10 and the plate 70 is rotatably supported by the shaft 13. The sleeves 67, 68 are slightly longer than the disk-like impact members 65, 66 are thick, thus permitting each member to move about the sleeve to which it is pivoted. Both impact members 65, 66 are alike and each is provided with an arcuately-shaped slot 74 through which the sleeves other than the sleeve to which the member is pivoted projects. The midpoint of each of the slots 74 is located 180 degrees from the axis about which the disk is pivoted, which axis also forms the radial center of the slot.

In the center of each disk there is provided an aperture 75 similar in configuration to the apertures 47 previously described and defined by similar arcuately-shaped and radial surfaces designated by the same reference characters. The slots 74 are of such length that the impact members are permitted a limited movement about the sleeves upon which they are pivoted, which movement is sufficient to cause the radial surfaces thereon to engage and disengage the radial surfaces of the anvil with which they cooperate.

The operation of both impact members 65, 66 is alike, therefore, it will be sufficient to describe only the operation of the impact member 65. Assuming that the flywheel or momentum member B is rotating in the direction indicated by the arrow R, the respective parts are shown in Fig. 8 in a position which they may occupy shortly after the primary impact between the shoulder or surface 52 of the impact member 65 with the surface or shoulder 20 of the anvil 18. When the shoulder or surface 52 of the impact member struck or impacted the shoulder 20 of the anvil 18, see Fig. 11, the impact member was rotated by the reaction produced, acting in the direction of the force arrow 60, in a clockwise direction about the sleeve 67 until the trailing

end of the slot 74 contacted the sleeve 68. This movement of the impact member 65 allowed the shoulder 52 and the surface 50 to pass around the anvil 18. As the shoulders 20, 52 disengage, the flywheel proper accelerates. The center of mass of the impact member is offset with respect to the axis of rotation of the clutch proper and the inertia of the impact member causes it to tend to lag behind the flywheel proper.

As soon as the surface 50 passes the rear end of the anvil 18 defined by the radial surface 21, which it is about to do, as shown in Fig. 8, the impact member 65 will be free to rotate in a counterclockwise direction about the sleeve 67. At this time the flywheel proper is accelerating and driving the impact member through the sleeve 67. The effect of the inertia of the impact member 65, as previously mentioned, causes the member to lag behind the flywheel proper until the leading end of the slot 74 engages the sleeve 68, that is, the impact member 65 will move from the position shown in Fig. 8 to the approximate position shown in Fig. 10 and the surface 52 will be in position to impinge the surface 20 of the anvil 18.

The foregoing method of operation is automatic but because of the variable frictional drag between the parts, it is not positive and to insure proper setting up of the impact member for the primary impact, the impact member 65 is provided with the internal radial surface or shoulder 54 which cooperates with the surface 20 on the anvil, if necessary, to assure proper resetting of the impact member. As shown in Fig. 8, the arcuately-shaped surface 50 is about to complete its passage over the anvil 18 and the radial surface 54 is approaching the impact surface 20 of the anvil and in the event the impact member 65 has not been reset by inertia, as explained above, by the time the shoulder 54 reaches the shoulder 20, the shoulder 54 will impact or strike the shoulder 20, as indicated in Fig. 9. The anvil 18 will offer resistance to rotation of the flywheel proper and will act against the shoulder 54 to rotate the impact member in a counterclockwise direction about the sleeve 67 until the leading end of the slot 74 engages the sleeve 68.

The force exerted by the anvil 18 against the member 65 will act in the direction indicated by the force arrow 61 and will have a moment arm of magnitude 62 about the center of the sleeve 67. As the member 65 rotates about the sleeve 67, the shoulders 20, 54 will be disengaged and the arcuately-shaped surface 51 will be permitted to pass about the anvil 18, see Fig. 10, whereupon the flywheel continues to rotate freely until impact is made between the surface or shoulders 20, 52, see Fig. 11. The condition existing when the shoulder 52 strikes the shoulder 20 is similar to that existing when the shoulder 54 strikes the shoulder 20 shown in Fig. 9, but the moment arm 63 of the impact force about the center of the sleeve 67 is much shorter than the moment arm 62, with the result that the impact or blow delivered to the anvil 18 is considerably greater and has considerable force.

When the shoulder 52 strikes the shoulder 20 of the anvil, the reaction produces a clockwise acceleration of the impact member 65 about the sleeve 67 which because of the relatively large mass of the impact member, adds to the force of impact, moves the trailing end of the slot 74 into engagement with the sleeve 68, disengages the shoulders 20, 52 and permits the fly-

wheel to resume rotation about the anvil. While the engaging surfaces 52 and 54 on the impact member 65 and the surface 20 on the anvil 18, respectively, are preferably radial, they may be varied slightly from a true radial position so as to facilitate their disengagement and eliminate all possibility of their hanging together, if desired. The shoulder 52, as shown, is adjacent to but trails the axis about which the impact member is pivoted to the driving member or flywheel proper and the moment arm 63 can be increased or decreased to vary the blow imparted to the anvil by varying the relative radial position of the pivot with respect to the shoulder 52, etc., or by varying the relative angular position of the shoulder 52 with respect to the pivot. The same is true of the shoulder 54 which, as shown, leads the pivot for the impact member.

The rotation of the impact member 65 about the sleeve 67 following impact between the shoulders 20, 52 occurs with considerable acceleration and as the opposite or trailing end of the slot 74 strikes the sleeve 68, the kinetic energy possessed by the impact member is transferred back to the rotating flywheel and serves to reduce the load of the flywheel upon the driving motor, thus permitting the motor to accelerate and build up speed rapidly between successive impacts. When impact occurs between the shoulders 20, 54 incident to setting up or preparing the impact member for the power or primary impact, it occurs only because the frictional forces which may be present resist the automatic, counterclockwise movement of the impact member that would otherwise afford uninterrupted passage of the member about the anvil between successive primary impacts. The energy used in this setting-up impact is small, being much less than that imparted by the flywheel or hammer to the anvil upon impact between the shoulders 20, 52, for the moment arm 62 at which the set-up force acts is much greater than the moment arm 63, and the direction of motion of the shoulder 54 is nearly collinear with the force arrow 61, whereas the direction of movement imparted to the shoulder 52 is almost perpendicular to the force arrow 60. Observation of the device in operation indicates that the impact member is usually set up for the power impact automatically by the inertia thereof, as previously explained, and without contact between the shoulders 20, 54. The anvils 18, 19 and the pivots for the impact members 22, 23 are offset 180 degrees, and two power blows or impacts which act as a couple are effected upon each rotation of the flywheel assembly B. Obviously any number of impact members and anvils may be employed, in which event any desired number of impacts will be obtained for each rotation of the flywheel.

The anvils 18, 19 and the impact members 65, 66 are symmetrical with respect to a central plane, from which it follows that the clutch or operative connection between the driving member B and the driven member 13 is reversible, therefore, it is only necessary to employ a reversible motor and the tool is suitable for tightening or loosening nuts, bolts, screws and the like. Referring to the operation of the impact member 65, when the drive is reversed the shoulders 21, 53 and 55 correspond with the shoulders 20, 52 and 54, respectively.

From the foregoing description of the preferred embodiment of the invention, it will be apparent that a novel and improved impact tool has been

provided whereby an impact of considerable force can be applied to a nut, bolt, screw or the like by a relatively light tool. The tool shown is simple in construction, inexpensive to manufacture, will operate satisfactorily for long periods of time with minimum wear and replacement and produces a maximum torsional blow for a predetermined size and weight. While the preferred embodiment of the invention has been described in considerable detail, the invention is not limited to the particular construction shown and it is my intention to hereby cover all adaptations, modifications and uses thereof which come within the practice of those skilled in the art to which the invention relates and within the scope of the appended claims.

Having thus described my invention, I claim:

1. In an impact driving connection, the combination of a rotatably supported driven member having an anvil, a rotatable driving member coaxially supported with respect to said driven member, a hammer element pivotally connected to said driving member for rotation therewith and angular movement relative thereto about an axis offset from but parallel with the axis of rotation of said driving member, said hammer element having an impact shoulder located between said axes and positioned so as to always trail its pivotal connection, and movable into and out of the path of said anvil for delivering a succession of impacts thereto, automatic means for effecting angular movement of said impact shoulder into the path of said anvil, and means responsive to the impact of said shoulder on the anvil for automatically effecting angular movement of said shoulder out of the path of said anvil in the same direction as that of said driving member.
2. In an impact driving connection, the combination of a rotatably supported driven member having an anvil, a rotatable driving member coaxially supported with respect to said driven member, a hammer element entirely surrounding said anvil and connected to said driving member for rotation therewith and pivotal movement relative thereto about an axis offset from but parallel with the axis of rotation of said driving member, the interior of said hammer element having a shoulder located between said axes and movable into and out of the path of said anvil by virtue of said pivotal movement for delivering a succession of impacts to said anvil, automatic means for effecting pivotal movement of said shoulder into the path of said anvil, and means responsive to the impact of said shoulder on the anvil for automatically effecting pivotal movement of said shoulder out of the path of the anvil.
3. In an impact driving connection, the combination of a rotatably supported driven member having an anvil, a rotatable driving member coaxially supported with respect to said driven member, a hammer element connected to said driving member for rotation therewith and pivotal movement relative thereto about an axis offset from but parallel with the axis of rotation of said driving member, an aperture in said hammer element into which said anvil extends and providing a first shoulder movable into and out of the path of said anvil by virtue of said pivotal movement for delivering a succession of impacts to said anvil, said first shoulder being moved out of the path of said anvil by virtue of its impact thereon, and means including a second shoulder in said aperture engageable with said anvil for moving said first shoulder into the path of said anvil.

4. An impact driving connection comprising a rotatably supported driven member, a rotatable driving member coaxially supported with respect to said driven member, a cylindrical hammer carrier between said members connected to said driving member for rotation therewith, an anvil on said driven member and within said carrier, a hammer element pivotally connected to said carrier for rotation therewith and pivotal movement relative thereto about an axis offset from but parallel with the axis of rotation of said carrier, an aperture in said hammer element into which said anvil extends and providing a shoulder movable into and out of the path of said anvil by virtue of said pivotal movement for delivering a succession of impacts to said anvil, automatic means for effecting pivotal movement of said shoulder into the path of said anvil, and means responsive to the impact of said shoulder on the anvil for automatically effecting pivotal movement of said shoulder out of the path of the anvil.

5. An impact driving connection comprising a rotatably supported driven member, a rotatable driving member coaxially supported with respect to said driven member, a cylindrical hammer carrier between said members connected to said driving member for rotation therewith, a pair of axially spaced and diametrically opposed anvils on said driven member and within said carrier, a hollow hammer element surrounding each anvil and pivotally connected to said carrier for rotation therewith and pivotal movement relative thereto, each hammer element having an internal shoulder movable into and out of the path of its respective anvil by virtue of said pivotal movement for delivering a succession of impacts to said anvil, and means in said carrier for limiting the pivotal movement of said hammer element.

6. An impact driving connection comprising a rotatably supported driven member having an anvil, a rotatably supported hammer carrier surrounding said anvil, means for rotatably driving said carrier, a hammer element, a pivotal connection between said element and carrier enabling rotation of said element with said carrier and relative pivotal movement therebetween, an aperture in said hammer element into which said anvil extends, and means on the wall of said aperture operatively associated with anvil during the rotation of said hammer element for automatically effecting pivotal movement of said hammer element, said means including a shoulder movable into and out of engagement with said anvil by virtue of said pivotal movement for delivering a succession of impacts to said anvil.

7. An impact driving connection comprising a rotatably supported driven member having an anvil, a rotatable driving member coaxially supported with respect to said driven member, a hammer element connected to said driving member for rotation therewith and pivotal movement relative thereto, an aperture in said element into which said anvil extends, and means on the wall of said aperture adapted to engage said anvil during the rotation of said element for automatically effecting its pivotal movement, said means including a shoulder movable into and out of engagement with said anvil by virtue of said pivotal movement for delivering a succession of impacts to said anvil.

8. An impact driving connection comprising a rotatably supported driven member having an anvil, a rotatable driving member coaxially supported with respect to said driven member, a hammer element connected to said driving mem-

ber for rotation therewith and pivotal movement relative thereto, an aperture in said element into which said anvil extends, and substantially diametrically opposed internal shoulders on said element adapted to engage said anvil during the rotation of said element for automatically imparting a succession of rotary impacts to said anvil and effecting the pivotal movement of said element.

10. An impact driving connection according to claim 8 in which said internal shoulders are located one to trail and the other to lead the connection between the hammer element and the driving member.

15. An impact driving connection comprising a rotatably supported member having an anvil, a rotatable driving member coaxially supported with respect to said driven member, a hammer element connected to said driving member for rotation therewith and pivotal movement relative thereto, and a duality of substantially diametrically opposed shoulders on said element adapted to alternately strike said anvil during normal rotation of the element whereby the striking shoulder is immediately shifted out of the path of the anvil by virtue of the impact and the opposed shoulder is automatically moved into the path of the anvil preparatory to the next impact.

11. An impact driving connection according to claim 10 in which said internal shoulders are located one to trail and the other to lead the connection between the hammer element and the driving member.

12. An impact driving connection comprising a rotatably supported driven member having an anvil, a rotatable driving member coaxially supported with respect to said driven member, a hammer element connected to said driving member for rotation therewith and pivotal movement relative thereto, and a duality of shoulders on said element adapted to alternately strike said anvil during normal rotation of the element, said anvil and shoulders having striking faces shaped and disposed relative to the connection between the hammer element and the driving member whereby each impact automatically effects movement of the striking shoulder out of the path of the anvil and movement of the other shoulder into the path of the anvil preparatory to the next impact.

13. An impact driving connection comprising a rotatably supported driven member having an anvil, a rotatable driving member coaxially supported with respect to said driven member, a hammer element connected to said driving member for rotation therewith and pivotal movement relative thereto, and means for effecting the pivotal movement of said element including a striking shoulder and a resetting shoulder on said element one located on one side and the other on the other side of the connection between said element and driving member, said shoulders being adapted to alternately strike said anvil during normal rotation of the element for imparting a succession of rotary impacts to said anvil, said striking shoulder being located closer to said connection than the resetting shoulder.

14. An impact driving connection according to claim 13 in which the striking shoulder is located to trail said connection.

15. An impact driving connection comprising a rotatably supported driven member having an anvil, a rotatable driving member capable of rotation in either direction, a hammer element connected to said driving member for rotation there-

with in either direction and pivotal movement relative thereto, said element having two sets of two shoulders, one set of shoulders being adapted to engage said anvil during normal rotation of the element in one direction and the other set of shoulders being adapted to engage said anvil during normal rotation of the element in the other direction for automatically effecting its pivotal movement and imparting a succession of rotary impacts to said anvil.

16. An impact driving connection according to claim 15 in which the shoulders of each set are located one ahead and one behind the connection between said element and driving member with respect to the direction of rotation of said element.

17. An impact driving connection according to claim 15 in which the shoulders of each set are located one ahead and one behind the connection between said element and driving member with respect to the direction of rotation of said element, the shoulder of each set located behind said connection being closer thereto than the shoulder ahead thereof.

18. An impact driving connection comprising a rotatably supported driven member, a radially extending striking face on said member, a rotatable driving member, a hammer element, a connection between said driving member and element affording rotation of the element with the driving member and relative angular movement therebetween about an axis offset from but parallel with the axis of rotation of said driving member, said hammer element having a shoulder movable into and out of the path of said striking face by virtue of said angular movement for delivering a succession of impacts thereto, at the time of impact said shoulder being parallel with said striking face and located behind said connection with respect to the direction of rotation of said driving member, and interengaging means between said element and driven member automatically effecting angular movement of said shoulder into the path of said striking face, said shoulder being moved out of the path of said striking face by virtue of its impact thereon.

19. An impact driving connection comprising a driven element and a driving element rotatably

supported on parallel axes, an aperture in said driving element into which said driven element extends, said driving element being capable of intermittent driving connection with said driven element, and means in said aperture between said elements automatically effecting and breaking said connection during each revolution of said driving element including a shoulder externally on said driven element and a shoulder internally on said driving element.

20. In an impact driving connection, the combination of a rotatably supported driven member having an anvil, a rotatable driving member coaxially supported with respect to said driven member, an impact member pivotally connected to said driving member for angular movement about an axis offset from but parallel with the axis of rotation of said driven member, said impact member having a shoulder adapted to impact said anvil, said shoulder being arranged and disposed in a manner enabling a line normal thereto at the time of impact to pass through the pivotal connection between the impact and driving members.

21. In an impact driving connection, the combination of a rotatably supported driven member having an external shoulder, a rotatable driving member coaxially supported with respect to said driven member, an impact member, a pin pivotally connecting said impact member to said driving member for angular movement about an axis offset from but parallel with the axis of rotation of said driven member, said impact member having a shoulder adapted to impact said shoulder on said driven member, said shoulder being disposed in a manner enabling a line normal thereto at the time of impact to pass through said pin.
